UNITED STATES PATENT OFFICE

2,521,708

THICKNESS COMPENSATOR FOR FLAT PLATE IRONERS

Edwin E. Foster, Austin, Tex.

Application February 15, 1943, Serial No. 475,955

10 Claims. (Cl. 38—25)

1

This invention relates to improvements in flat plate ironers of the type in which a permanently stored energy unit supplies the pressure for the ironing force and this unit is movable to direct the force of the unit between and away from the ironing members. Actually, this invention involves an improvement in a thickness compensator for the ironing members and a particular mounting for the operating handle to shorten the length of travel compared with the travel of the head member of the ironer.

It is therefore an object of the invention to provide an automatically operative thickness compensator, actuated by the head member arm or by the stored energy unit which is operative just prior to or simultaneously with the application of the ironing force between the ironing members. A further object resides in the provision of a movable or pivoted bed member to compensate for the thickness of the material being ironed and the application of the compensating elements operable in the stationary frame of the machine or ironer.

Another object of the invention resides in the provision of mechanism to reduce the extent of travel of the operating handle of the ironer relative to the extent of travel of the head or movable member of the ironer. A further object resides in an adjustable mounting of the handle to a side position and out of the way when the machine is not in use. In such latter position the handle acts to keep the head and bed members separated a slight distance to permit the head member to cool off and the bed member to dry out after ironing.

Further objects will be apparent from the following description, when considered in connection with the accompanying drawings, in which:

Figure 1 is a side elevation of the ironer in the press open position.

Fig. 2 is a similar view of the machine in the press closed position before the application of ironing pressure.

Fig. 3 is a similar view of the machine in the pressure applied position.

Fig. 4 is a front elevation of the machine in the press closed position before the application of ironing pressure.

Fig. 5 is a rear elevation of the machine in

2

the press closed position before the application of pressure with a part in section.

Fig. 6 is a side elevation of the machine partly in section in the pressure applied position.

Fig. 7 is a perspective view of the handle mounting means.

Fig. 8 is a plan view of the machine.

Fig. 9 is a side elevation partly in section of a modified ironer in the press closed position just before the application of pressure.

Fig. 10 is a sectional view through the stored energy unit and adjacent parts of the machine of Fig. 9.

Fig. 11 is a side elevation of the lower forward end of the ironer showing modified details.

Fig. 12 is a front elevation of the ironer of Fig. 11.

Fig. 13 is a side elevation of the lower forward end of the ironer showing further modified details, and

Fig. 14 is a side elevation of the ironer of Fig. 13.

The press or ironer includes a substantially U-shaped base frame member 11 having a front angle member 12 mounted on suitable feet or rubber discs 13, a bed member or buck 14 and a head or movable member or shoe 15. The bed member 14 may be provided with a padding material as usual and the head member 15 may be made of metal such as aluminum heated by suitable well known electric heating units (not shown).

The bed member 14 is suitably secured on one end 16 of a U-shaped lever arm 17 pivoted on the other end 18 in the upright section 19 of the frame member 11 on a pivot shaft 20. A compression spring 21 bears on one end on the frame 11 and the other end under the bed member 14 to constantly urge the latter upwardly, the purpose of which will be explained. The end portion 16 of the arm 17 is provided with a bar 22 having a plurality of ratchet teeth 23 cut therein, the latter cooperating with a pawl or locking member 24 pivoted at 25 in the front end of the frame member 11, Fig. 6. A link 26 is pivotally connected at 27 to the pawl 24, the other end having a small spring 28 bearing against a bell crank lever 29. A small tension spring 26' is secured at one end to the frame 12 and the other end to the link 26 to urge latter to the left, Fig. 6. The lever 29 is pivoted at 30 in the rear part

of the frame 11, Figs. 5 and 6, and is provided with a projecting trigger finger 31 extending through one side of the frame member through an elongated perforation 32.

The head member 15 is provided with suitable electric current adjusting buttons 33 and an electric cord 34, Fig. 8, for the heating means (not shown) in the head member. The latter is shown as mounted on a horizontal rod or pivot 35, Fig. 8, to a movable arm 36 but any other type of mounting may be utilized. The arm 36 is suitably stamped from sheet metal or it may be formed from several pieces. As shown this arm has a top section 37 extending from the head member 15 to the edge 38, Figs. 2 and 6, and two side sections 39 extending the full length of the arm. Each side section 39 is provided with a pivot pin 40 each mounted in one side of the frame 19, Fig. 5.

The permanently stored energy unit which is utilized to provide the ironing pressure, is similar in construction and operation as shown and described in my prior Patent No. 2,231,897, of February 18, 1941. In the form of invention of Figs. 1 to 8 the unit 41 comprises a frame 42 pivoted on pins 43 each secured in a side section 39 of the arm 36. A compression spring 44, Fig. 6, is mounted in a cylindrical housing 45 pivotally mounted on a pin 46, the latter being secured in ball bearings 47, Fig. 1, in the frame 19. The spring 44 bears at one end on the end 48, Fig. 6, of the housing 45 and the other end on a disc 49, the latter being secured at one end of a rod 50 pivoted in ball bearings 51 in two lugs 52. These lugs 52 are secured in an end wall 53 of the frame or casing 42, by means of bolts 54.

The arm 36, together with its head member 15 and the energy unit 41, are operated by means of a hand lever 55 having a hand grip 56 at the front end of the machine. The hand lever is removably mounted in a socket 57. A winged set screw 58 secures the hand lever 55 in place. The socket 57 is secured to a shaft 59 rotatably mounted in lugs 60 bolted on the top surface of the casing 42. A depending link 61 is secured to or is made integral with the shaft 59 and extends through an opening in the top of the casing 42, Fig. 6. This link is secured to a second link 62 which is operatively connected to the pin 46 which is the axis of rotation for the cylinder 45 of the stored energy device. The socket 57 has a short cut-out portion 63 and the hand lever 55 is provided with a stop button 64. As shown in Fig. 8, the lever 55 may be adjusted at an angle 65' relative to the longitudinal axis of the arm 36 when the ironer is not in use which is quickly accomplished by unscrewing the set screw 58 a number of turns and rotating the lever 55 in its socket 57 limited by the cut-out portion 63 and the set screw 53, Fig. 3. The casing 42 will thus abut against the stop button 64, since the head member and its arm tend to rise due to spring 44 and in that position the head and bed members will be separated about one inch permitting the ironing surfaces to dry out or off and the ironer is thus more compact when not in use.

In the form of the invention shown in Figs. 9 and 10 the base frame 65 has a telescoping casing 66 and 67 surrounding the spring 68, the pawl 69 and the ratchet post or support 70. The bed member 71 is suitably secured on the post 70 and the latter is integral with the supporting lever 72 of U-shaped configuration pivoted on the pin 73 in the upright back portion 74 of the

frame. The head member 15 is suitably secured to the arm 76 pivotally mounted on pins 77 secured in the upright portion 74.

The permanently stored energy unit 78 is similar to the unit 41 of Figs. 1 to 8 except that in the form of invention of Figs. 9 and 10 a tension spring 79 is utilized instead of a compression spring. This spring 79 is pivotally mounted on one end on a pin 80 mounted in ball bearings 81 in the upright frame portion 74, Fig. 10, and the other end of the spring is secured to a link 82 rotatably mounted in a bracket member 83 secured to the back wall 84 of the unit casing 85. The casing or frame 85 is rotatably mounted by means of ball bearings 86 on pins 87 secured in the side parts 88 of the arm 76.

An operating handle 89 having a grip portion 90 is pivoted at 91 to the top surface of the casing 85 and is connected to a lever 92. This lever 92 is connected to a rod 93 which is secured at 94 to the pin 80.

The pawl 69 is pivoted on the rod 95 in the frame 65 and has a lever arm 96 connected thereto at the end 97. A spring 98 is mounted on the other end bearing at one end on a nut 99 and on the other end on a bell crank lever 100 and an abutment 101. The bell crank lever 100 is pivoted at 102 in the upright portion 74 of the frame and has a projecting finger 103 adapted to cooperate with and project into the path of the casing 85.

The ironer of Figs. 1 to 8 operates as follows:

Fig. 1 illustrates the non-ironing position with the force of the stored energy unit 41 passing in its circuit through the casing 42, side sections 39, and frame 19, that is practically the full ironing pressure of the spring 44 is held by the frame parts of the base and arm members. The article to be pressed is laid out on the bed member 14 and the grip 56 of the lever 55 is now grasped and pulled down to the position of Fig. 2 to bring the head member 15 simultaneously down on the bed member 14 and on the article to be ironed. As the article to be pressed has some thickness the head member 15 will force the bed member 14 down slightly dependent upon the amount of thickness and just when pins 43 are practically in coincidence with the pin 46, one side section 39 of the arm 36 will abut against the finger 31 to slightly rotate the bell crank lever 100 counter-clockwise, Fig. 6, resulting in a pull to the right, Fig. 6, to move the pawl 24 into the nearest adjacent tooth 23 to prevent further downward movement of the bed member 14 which latter through portion 16 and arm 17 pivots around shaft 20. Further downward movement of the handle lever 55 from the position of Fig. 2 to that of Fig. 3 results in shifting the energy unit 41 upwardly to change the force circuit of the pressure of the spring 44 through the head and bed members for the ironing pressure at the same time maintaining the pawl in contact with the rack bar 22. The actual operation of the stored energy unit is completely described in my said prior patent. It will be seen from the drawings that during the movement of the head member 15 from the position of Fig. 1 to that of Fig. 2 that the handle lever 55 has traveled or moved only a fraction or less than half the distance of the head member, which is due to the fact that the handle lever 55 pivots around the pin 46 as an axis and not the axis of the shaft 59. When the handle is moved from the position shown in Fig. 1 to the position shown in Fig. 2, the link 62 stays practically stationary in relation to axis 46, but the point 59 is above the

pivot point 4 of the arm 39 and causes the arm 39 to pivot about the point 40. The link 61 and lever 55 form a lever with the point 59 acting as the point of contact against the arm 39. In other words, referring to Fig. 9, the point 91 is above the point 40 and urges the head downward as the handle 55 is moved downward. This causes a slight movement of the links 61 and 62 but there is no relative movement of the links from the position of Fig. 2 to that of Fig. 3, since all parts move together. The purpose of the initial small travel of the handle lever is to limit the total movement of such lever which is necessary to move not only the head member to the bed member but also to move the energy unit. Furthermore the particular mounting of the handle lever makes it unnecessary to provide two operating handles, that is, one for the head member and one for the energy unit.

As described in my prior Patent No. 2,231,897, a small portion of the energy of the spring 44 is expended for counter-balancing the head 15 and arm 36, said energy being easily restored upon each downward pull of the handle lever 55, that is, at the beginning of each ironing step. Thus the spring 44 maintains the parts in the press open position of Fig. 1.

After each ironing step, that is upon moving the parts from the position of Fig. 3 to that of Fig. 1, the finger 31 is released whereupon the spring 21 forces the bed member 14 back to its original position, Fig. 1.

When all the ironing has been completed the ironer should not be left in the press closed position, Fig. 3, since the usual padding on the bed member 14 will not readily dry out and the metal contacting surface of the head member 15 may tarnish or be otherwise affected by the moisture. To leave the ironer in the press open position, Fig. 1, takes up too much space. To avoid the foregoing drawbacks the ironer is adjusted in the position of Fig. 8 with the handle lever 55 in the position indicated by the dotted lines 65'. This is accomplished by placing the parts in the position of Fig. 2 then unscrewing the set screw 58 and rotating the handle lever 55 to the right, Fig. 8, until the set screw reaches its limit of movement as defined by the cut-out portion 63 in the socket 57. Then by releasing manual hold on the head member 15 the arm 36 and its head member 15 will move up slightly, about one inch for the latter, until the upper surface 42 of the energy unit 41 contacts the stop button 64.

The press of Figs. 9 and 10 operates in a manner similar to that of Figs. 1 to 8. In this construction the automatic thickness compensator operates by means of the casing 85 to one end of which the energy unit is secured.

The handle lever 55 may if desired be removed from the socket 57 by completely unscrewing the set screw 58 which is threaded in the end of the lever 55. When the handle lever is in the positions shown, the set screw 58 is not only wedged by its inner end surface against the inside surface of the socket 57 but also against one side of the cut-out portion 63. In the position of the handle lever 65 shown in dash lines in Fig. 8 the set screw 58 has merely been loosened and the lever 55 rotated to the right in its socket until the set screw abuts against the other side of the cut-out portion 63.

It may be desirable to provide two pawls instead of one in order to secure a more accurate adjustment of the position of the bed member 14 to compensate for the thickness of the material to be pressed. Figs. 11 to 14 illustrate two modi-

fied constructions in which two pawls are used instead of one.

In Figs. 11 and 12 a pair of pawls 110 and 111 are rotatably mounted on a rod 120 by means of bearings 113 and 112 respectively and these pawls are connected to the actuating link 26 by means of a forked end member 114. Each pawl is spring pressed by means of a separate spring 116 bearing against a lug 115 and these pawls cooperate with a rather wide ratchet member 109 having teeth thereon. The pawl 110 is slightly shorter than pawl 111, Fig. 12, and by this construction a finer adjustment is possible.

In Figs. 13 and 14 the structure of the double pawls is similar except that pawls 111 are each provided with a plurality of teeth, Fig. 13.

The operation of the double pawl devices is believed to be obvious when it is considered that the double pawls provide for a finer engagement thereof with the tooth or teeth of the ratchet member at the point where the bed member has reached its extreme bottom position due to the thickness of the material to be ironed and possibly also slight compression of the padding on the bed member.

I claim as my invention:

1. In a flat plate ironer having a base frame and movable arm with cooperating and movable head and bed members of which the head member is secured to the arm and the bed member is supported by the base frame with slight vertical movement and an energy unit connected to the frame and arm to supply the ironing pressure when the head and bed members are in closed position, an automatic thickness compensator comprising a ratchet member mounted on the bed member, a pawl pivotally mounted on the frame, and means operative by contact with the arm after the head member contacts the work on the bed member to move the pawl into contact with the ratchet member to hold the bed member in the adjusted position in dependence upon the thickness of the material to be ironed.

2. In a flat plate ironer having a base frame and movable arm with cooperating and movable head and bed members of which the head member is secured to the arm and the bed member is supported by the base frame with slight vertical movement and an energy unit connected to the frame and arm to supply the ironing pressure when the head and bed members are in closed position, an automatic thickness compensator comprising a ratchet member mounted on the bed member, a pawl pivotally mounted on the frame, and means operative by contact with the energy unit after the head member contacts the work on the bed member to move the pawl into contact with the ratchet member to hold the bed member in the adjusted position in dependence upon the thickness of the material to be ironed.

3. In a flat plate ironer having a base frame and a movable arm with cooperating head and bed members of which the head member is secured to the arm and the bed member is supported by the base frame with slight vertical movement and an energy unit connected to the frame and arm to supply the ironing pressure when the head and bed members are in closed position, said bed member being movably mounted with respect to the frame and said energy unit being operative to apply the ironing pressure at a definite position of the head member relative to the frame, an automatic thickness compensator comprising an adjustable mounting for the bed member, and means mounted in the frame with a

portion thereof extending into the path of movement of the arm to hold the bed member in an adjusted position in the closed position of the ironer in dependence upon the thickness of the material to be ironed, said means including latch means responsive to movement of said energy unit to a point adjacent said definite position to lock the bed member against further downward motion.

4. In a flat plate ironer having a base frame and a movable arm with cooperating head and bed members and an energy unit connected to the frame and arm to supply the ironing pressure when the head and bed members are in closed position, said bed member being movably mounted with respect to the frame and said energy unit being operative to apply the ironing pressure at a definite position of the head member relative to the frame, an automatic thickness compensator comprising an adjustable mounting for the bed member, and means mounted in the frame with a portion thereof extending into the path of movement of the energy unit to hold the bed member in an adjusted position in the closed position of the ironer in dependence upon the thickness of the material to be ironed, said means including latch means responsive to movement of said energy unit to a point adjacent said definite position to lock the bed member against further downward motion.

5. An automatic thickness compensator for a flat plate ironer having relatively movable head and bed members and a frame and an arm pivoted to the frame and carrying the head member, comprising a U-shaped lever carrying the bed member at one end and pivoted at the other end to the frame, said lever having a series of ratchet teeth adjacent the bed member, a pawl pivoted in the frame and cooperating with the ratchet teeth, and means connected to the pawl and projected into the path of movement of the arm in such manner that when the head member contacts the material to be ironed and moves the bed member downwardly a distance approximately equal to the thickness of the material to be ironed, the arm will actuate said means to move the pawl into the ratchet teeth to prevent further downward movement of the bed member.

6. An automatic thickness compensator for a flat plate ironer having relatively movable head and bed members and a frame and an arm pivoted to the frame and carrying the head member, comprising a U-shaped lever carrying the bed member at one end and pivoted at the other end to the frame, said lever having a series of ratchet teeth adjacent the bed member, a pawl pivoted in the frame and cooperating with the ratchet teeth, a link connected at one end to the pawl, and means connected to the other end of the link and projecting into the path of the arm in such manner that when the head member contacts the material to be ironed and moves the bed member downwardly at a distance approximately equal to the thickness of the material to be ironed, the arm will actuate said means and link to move the pawl into the ratchet teeth to prevent further downward movement of the bed member.

7. An automatic thickness compensator for a flat plate ironer having relatively movable head and bed members and a frame and an arm pivoted to the frame and carrying the head member, comprising a U-shaped lever carrying the bed member at one end and pivoted at the other end to the frame, said lever having a series

of ratchet teeth adjacent the bed member, a pawl pivoted in the frame and cooperating with the ratchet teeth, a link connected at one end to the pawl, and a bell crank lever connected to the other end of the link and projecting into the path of the arm in such manner that when the head member contacts the material to be ironed and tends to move the bed member downwardly a distance approximately equal to the thickness of the material to be ironed, the arm will move the pawl, by means of the link and bell crank lever, into the ratchet teeth to prevent further downward movement of the bed member.

10. In a flat plate ironer having cooperating and relatively movable head and bed members and a frame and an arm pivoted to the frame and carrying the head member, the combination with a stored energy unit pivoted on the arm and frame to supply the ironing pressure when the head and bed members are in closed position, and an automatic thickness compensator comprising a U-shaped lever carrying the bed member at one end and pivoted at the other end to the frame, said lever having a series of ratchet teeth adjacent the bed member, a pawl pivoted in the frame and cooperating with the ratchet teeth, a link and a bell crank lever connected to each other and the link to the pawl, said bell crank lever extending into the path of movement of the arm in such manner that when the head member contacts the material to be ironed on the bed member and moves the bed member downwardly a distance approximately equal to the thickness of the material to be ironed, the arm will actuate said bell crank lever and link to move the pawl into engagement with one of the ratchet teeth to prevent further downward movement of the bed member, and a spring between the frame and the bed member to force the latter upwardly to its initial position after each ironing operation.

15. In a flat plate ironer having cooperating and relatively movable head and bed members and a frame and an arm pivoted to the frame and carrying the head member, the combination with a stored energy unit pivoted on the arm and frame to supply the ironing pressure when the head and bed members are in closed position, and an automatic thickness compensator comprising a U-shaped lever carrying the bed member at one end and pivoted at the other end to the frame, said lever having a series of ratchet teeth adjacent the bed member, a pawl pivoted in the frame and cooperating with the ratchet teeth, a link and a bell crank lever connected to each other and the link to the pawl, said bell crank lever extending into the path of movement of the arm in such manner that when the head member contacts the material to be ironed on the bed member and moves the bed member downwardly a distance approximately equal to the thickness of the material to be ironed, the arm will actuate said bell crank lever and link to move the pawl into engagement with one of the ratchet teeth to prevent further downward movement of the bed member to compensate for the thickness of the material to be ironed, and means to move the bed member and U-shaped lever to their normal raised position after each ironing operation.

20. In a flat plate ironer having a base frame and movable arm with cooperating and relatively movable head and bed members, of which the head member is secured on the arm and the

bed member is supported by the base frame with slight vertical movement, an automatic thickness compensator comprising two parts of which one is mounted on the bed member and the other is mounted on the frame, and means operative by contact with the arm after the head member contacts the work on the bed member to move one part into contact with the other part to hold the bed member in the adjusted position in dependence upon the thickness of the material to be ironed.
